UNITED STATES PATENT OFFICE.

GAIL D. BEAVER, OF PHILADELPHIA, PENNSYLVANIA, ASSIGNOR TO HASLETT CHUTE AND CONVEYOR COMPANY, OF OAKS, PENNSYLVANIA, A CORPORATION OF PENNSYLVANIA.

INTERLOCKING DOOR FOR WASTE CHUTES.

Application filed July 22, 1924. Serial No. 727,415.

My invention relates to the protective closure of passage ways by double doors and to means for opening and closing the double doors. It finds its best illustration 5 in protection of branches of waste chutes at any floor or floors.

Waste chutes usually extend vertically from the basement to the top of a building and inlet branches are provided at 10 the different floors to receive sweepings and waste matter for delivery to the basement.

To avoid risk of fire spreading from floor to floor through the chute it is desirable to have the chute everywhere at all 15 times sealed from the interior of the building, and the main purpose of my invention is to provide improved, inexpensive and efficient means for absolutely sealing the chute 20 at all times from the interior of the building.

A further purpose is to provide improved interlocking operating mechanism for doors 25 so related to them that it will operate either door separately and when the one door is being operated will lock the other door shut. The operating mechanism may be locked at its intermediate position so as to lock both doors or may be arranged to lock both doors 30 by its position alone.

A further purpose is to have the doors pivoted and simultaneously positioned by means of pivoted operating mechanism that simultaneously mates with and positions or 35 separately and successively operates other rotary mechanism connected with the individual doors. I thus hold both doors shut where the operating mechanism is in the medial position and may lock them shut, either by locking the operating mechanism, 40 (Figure 3) or by the position of the parts of this mechanism (Figure 7).

By movement of the operating mechanism in one direction I lock (or continue to maintain the locked condition, as in Figure 7) one door and open the other while by movement of the operating mechanism in the opposite direction I lock (or continue to main-

tain the locked condition of, as in Figure 50 7) the second and open the first.

Further purposes will appear in the specification and in the claims.

Chutes already exist with interlocking double doors in which the interlocking ensures closure of one door when the other is 55 fully open yet does not ensure closure at other times, permitting both doors to be partially open at the same time. This condition defeats, in a measure, the purpose for which the doors are installed. With my interlocking doors, common means is provided for operating both doors, one at a time and neither door can move at all unless the other door is entirely closed. Neither door can operate the other. Locking means 60 may be provided for the individual doors to prevent them from moving in response to pressure upon the doors, or they may be left free to move (either door but not both) 65 in this way, as preferred.

I have preferred to illustrate but one main type with variations in the locking means provided for the operating mechanisms and in the chutes, selecting a form which has proved to be practical, effective, inexpensive 70 and thoroughly reliable and which at the same time well illustrates the principles of my invention.

Figure 1 shows a broken side elevation illustrating my invention.

Figure 2 is a plan of Figure 1.

Figure 3 is a front elevation of Figure 1.

Figure 4 is an enlarged detail illustrating the operating gears when both doors are closed.

Figure 5 is a view similar to Figure 4 but with the gears in position corresponding to the outer door being open wide.

Figure 6 is a similar view showing the gears in position corresponding to that in 90 which the outer door is closed and the inner door is open wide.

Figure 7 is an enlarged detail showing operating gears in which the operating gear locks both driven gears in closed positions of 95 the doors closed by them.

Figures 8 and 9 are fragmentary sections of the chute showing forms slightly variant from that of Figures 1-3.

In the drawings like numbers refer to like parts.

Describing the invention in illustration and not in limitation and referring to the drawings:

The main chute 15 runs from the basement 10 to the roof, a small section thereof, that at a single floor, being shown in the figures. A requisite condition for fire protection is that there shall never be direct connection between the chute and the interior of the 15 building.

Each lateral chute or inlet 16, giving access to the chute at a floor, is supplied with double doors 17 and 18. One only of these should be capable of opening movement 20 while the other is kept tightly closed. Assuming that the outer door 18 is open, sweepings and waste matter, laundry or other material for delivery to the basement is passed through the opening but cannot pass 25 from the lateral chute into the main chute because the inner door 17 is closed tight, preventing direct opening between the main chute and the room into which the door 18 opens.

30 So far as I am aware I am the first to provide efficient common means for positioning, operating and controlling both doors in a way to wholly avoid this danger of direct opening between the chute and room.

35 The outer door 18 is connected with a hinge, shaft or pintle 19 (see Figures 7, 8 and 9) which rigidly carries the gear 20 and the inner door 17 is connected with a similar hinge, shaft or pintle 21 rigidly carrying the gear 22 so that the positions of the doors are controlled, respectively, by these gears.

40 The intermediate gear 23 is mounted upon a shaft or pin 24 upon which it may turn or which may turn it as preferred. The hand lever 25 may evidently be connected with the shaft, where the shaft drives the gear or directly with the gear. The gear is so constructed and connected as to operate both doors, one at a time. 45 The hand lever 25 is provided with catch 26 at the position which corresponds to the outer door open and inner door closed, the purpose of this catch being to hold the outer door open when matter is being dumped into the chute.

50 The driving or intermediate gear 23 has teeth 27 cut on a portion only of its outer circumference, the remaining portion 28 of the circumference being circular and having 55 a radius corresponding approximately to that of the pitch circle of the teeth.

The gear 20, which positions the outer door, has full sized teeth 29 for a portion of the circumference and has two or more teeth

30 and 30', at one end of the toothed portion 65 used, cut away to give a concave surface or separated contact edges with a hollow between to fit the convex circular arc portion 28 of the gear 23. As the surface at 31, shown as a recess between the two teeth is 70 not used, the concavity not needing to be as deep as this, it is immaterial whether it be left cut a recess, as would be the case in the normal cutting of the gear, or be filled in to the pitch line. Likewise it is immaterial as to the contour of the surface 31', which is shown a circle. It could be filled with teeth or flattened or have other different contours as it is not used. 75

In the same way the upper gear 22 operating the inner door 17 has teeth 32 full size around a portion of its circumference and two or more teeth 33, 33' cut to cooperate with the convex arc 28 of the intermediate wheel. 80

85 For the same reasons explained in connection with gear 20, it is immaterial from a mechanical standpoint whether the surface recessed at 34 be a recess inside its pitch circle or not and the surface at 34' may be of 90 any contour.

95 The important thing is to give the driven gears and driving gear contours adjacent to their full toothed surfaces such that the driving gear shall act as a stop for the driven gears, permissible for both in the neutral position of the driving gear (Figure 7), but in any event for each one of them just the moment the other has moved to begin opening of its door. This interfitting stop connection is illustrated by one form of the 100 so-called Geneva stop mechanism or motion.

105 It will be evident that the sizes and proportions of the gears as well as the extents of openings of the doors will determine whether or not any of the teeth upon gear 23 which engage the teeth of gear 20 (beginning with the left end of the line of teeth in Figure 5) will also come into mesh with the teeth of gear 22 (with which the teeth of gear 23 begin to mesh from the right end of the line of teeth) or whether the two "sets" of engaging teeth upon gear 23 will overlap, as would be the case with a smaller diameter of gear 23 or with a larger throw 110 of the doors. In the illustration shown they do not overlap and one of the teeth shown may not engage with the teeth of either of the gears 20 or 22, depending upon the extent of opening given to the inner door. 115 For this reason the arc of teeth upon gear 23 may be interpreted to form two arcs. Where there is a gap between the teeth from the to ends engaging the two gears they may even form two arcs or sets of teeth and the teeth shown on gear 23, even when uninterrupted may be viewed as forming two sets.

120 For much the same reason, the range of

movement of gear 23 in operating each of the other gears may be short enough so that part of the cylindrical perimeter of this gear will not be utilized in stop engagement with either of the two gears 20 or 22, permitting this perimeter to be interrupted to form two separated sections, with the result that the full arc shown may be viewed as two circular arcs adjoining opposite ends 10 of the arc or arcs of teeth upon gear 23.

With a smaller diameter of gear 23 with respect to the other gears or with a larger throw of the doors, causing substantially all of the teeth of gear 23 to engage at each 15 driving operation, namely with the teeth of gear 20 and also (at another time) with the teeth of gear 22, substantially all of the perimeter shown at 28 as a circular arc would sweep past and maintain locking engagement with each of the cooperating locking 20 concavities (but one only at a time) of the two gears 20 and 22.

These variations in the operation will be well understood by those skilled in the art 25 as matters of design only in view of my disclosure.

Since the shaft 21 passes through the chute it is desirable to protect against the shaft catching laundry or other articles 30 passed down the chute from above. The guard 35 is used for this purpose.

Except as the handle 25 is held to prevent turning of the shaft 24, or the shaft is otherwise held, either of the doors in the construction shown in Figures 1-6—but one 35 only of the doors at a time—will yield to an opening pressure and turn the parts to or toward the positions seen in Figure 5 or Figure 6. The simplest and most convenient 40 means of preventing unauthorized or accidental opening of either door lies in locking the handle in its "neutral" position by a bracket 36 and lock 37.

In the form seen in Figure 7 locking is 45 secured by having the locking surface of gear 23' (i. e., that which prevents movement of gears 20 and 22, one at a time, in Figures 5 and 6,) so positioned as to engage teeth 30 and 33 in the neutral position of the 50 parts illustrated in Figure 7. That is, the convex locking surface 28', which is a part of the driving, master or intermediate gear which performs the locking, is either made a larger part of the circumference of gear 55 23 than of gear 23' or the gears 20 and 22 are displaced more to the left in the figures so as to engage more of this surface in the neutral position of the driving gear. In whichever 60 event both gears 20 and 22 are stopped from turning by the mere position of the driving gear.

Both gears 20 and 22 are thus locked by the surface of the operating gear when the doors are closed and the operating gear is 65 in neutral position. Neither gear can be

moved, and neither door can be opened until the operating gear is turned.

Figures 4-7 show convenient forms of Geneva motion from among various forms of this mechanism suited to my use.

Either door is intended to close by gravity when the handle 25 is released and this is true not only in the form of Figures 4, 5 and 6 but also in that of Figure 7, however as one door only can be open at a time so 70 also one door only can close. That this tendency to close is true of the outer door is quite apparent. In Figure 1 the frame against which the inner door closes is so set as to be in line with the normal hanging 75 position of the door so that it will close by gravity, and closure is assisted by the weight of the operating handle. A spring 38 could also be used, as in Figure 8, to ensure automatic closure of the inner door.

When in the position of Figure 4, which is that corresponding to both doors being shut, the intermediate, driving or operating gear 23 is in position to open either door according to the direction in which it may be turned; if moved to open the outer door, that is toward the position of Figure 5 the upper gear 22 becomes locked by reason of the mating engagement between the arc portion 28 of the operating wheel and the limiting walls of the concavity represented by teeth 33 and 33' of the gear 22. It is thus evident that when the operating gear is turned to open the outer door the inner door 85 is locked shut.

In exactly the same way, after the lateral chute has been charged with dirt and sweepings from the floor, the first effect of operating the handle from its lower dotted position (Figure 1) to its full line (neutral) position there is to close the outer door. If the driving gear of Figure 7 be used, the outer door is not only closed but is also locked, by the time the neutral position is 100 reached as there is complete locking of both doors at neutral position. If the form of Figures 4, 5 and 6 be used, locking of the outer door does not take place until the handle is moved further but the inner door is unlocked and further movement of the handle opens the inner door. In the form of Figure 7 the handle must move upwardly beyond the neutral position before the locking of the inner door is released.

In the form shown in Figure 7, since the operating gear in neutral position affords a lock for preventing movement of either of the gears 20 and 22, neither door can be opened accidentally or unauthorizedly while the operating gear 23' is in neutral position.

In Figures 8 and 9 special constructions are shown for giving the inner door additional pressure tending to close it against its opening and hold it there. In Figure 8 this special means comprises a spring 38 which 120

may be wrapped about the pintle and one end of which will press against the door to tend to hold it closed.

In Figure 9 the door 17' is tangent to the inside of the pintle upon which it is carried instead of being tangent to the outside of this pintle as in Figure 1 with the result that the door tends to close beyond the position shown in Figure 9 causing reliable closure against a surrounding flange 39.

I recognize that this operating mechanism is suited to uses for protecting other passages than chute passages and have therefore used the chute form as an illustration upon which claims of broader scope are founded.

A great advantage of my invention is its practically fool-proof character in that the doors cannot both be opened at one time even in the case of carelessness by the users. The interior of the main chute cannot at any time come into direct communication with the room.

It will be obvious that those skilled in the art will see modifications and changes which may be made in my invention without departing from the spirit and scope and it is my purpose to claim all such herein as come within the reasonable spirit and scope of my invention.

Having thus described my invention, what I claim as new and desire to secure by Letters Patent is:—

1. A chute, a pair of swinging spaced doors for the chute each having a tendency to close, driven gears respectively connected to turn when the doors turn, an intermediate driving gear between the driven gears adapted to drive the driven gears to open either door and, when free, to be driven by the closing tendency of either door to permit closing of the door automatically and stop devices between the driven gears and the driving gear preventing opening of either door when the other is not closed.

2. A chute, a pair of swinging spaced doors for the chute respectively pressed toward closed position and each having closing movement in a direction opposite to that of the other, driven gears respectively turning when the doors turn, an intermediate driving gear between the driven gears adapted to drive the driven gears to open either door according to its direction of turning and, when free, to be driven by the closing tendency of either door to permit closing of the door automatically, means for turning the driving gear and stop devices between the driven gears and the driving gear preventing opening of either door when the other is not closed.

3. A chute, a pair of pivoted doors therein, a gear upon each door pivot turning with the door, an intermediate gear between the two gears and stop interlocking between the intermediate gear and first gears where-

by the position of the intermediate gear corresponding to open or partly open position of either door stops the gear upon the pivot of the other door from turning.

4. A chute, a pair of pivoted doors therein, a gear upon each door pivot turning with the door, intermediate gearing mechanism between the two gears and stop interlocking between the intermediate gearing mechanism and first gears whereby the position of the intermediate gearing mechanism corresponding to open or partly open position of either door stops the gear upon the pivot of the other door.

5. A chute, oppositely swinging doors therefor, and driving and driven gearing controlling the position of said doors each having gear teeth and cooperating stop motion surfaces, characterized by engagement of the stop surfaces of the driving gearing and the driven gearing for either door to hold that door closed and at the same time by engagement of the teeth of the driving gearing and of the driven gearing for the other door to open said other door.

6. In a chute, a pair of doors swinging in opposite directions to close the chute, two gears connected one with each door to swing with the doors, and each having teeth and an adjoining stop motion element and intermediate mechanism having teeth for engagement by the teeth of either gear and adjoining the teeth adapted to cooperate with the stop motion elements of the two gears, one at a time, whereby opening of either door turns the intermediate mechanism and applies the stop motion to the gears connected with the other door.

7. The combination of a chute, pivoted doors therein having parallel shafts, and means comprising gearing on the two shafts and gearing cooperating therewith for opening either door while holding the other door closed.

8. A pair of doors and driving mechanism for opening either door while holding the other closed, comprising a driving gear having teeth throughout an arc of its circumference and, at each end of the arc, a convex smooth surface, in combination with driven gears on opposite sides of the driving gear, connected with the doors, having teeth which cooperate with teeth upon the driving gear and spaced contact surfaces adjacent the teeth cooperating with the convex surfaces respectively of the driving gear to free the driven gears from driving engagement with the driving gear and lock them against movement.

9. The combination of a chute, a branch chute thereto, inner and outer pivoted doors in the branch, a gear for successively positioning the doors by its angular position and having both operating and locking parts and connections between the gear and doors

whereby when moved angularly throughout its range of motion in one direction the gear successively closes the outer door, locks it shut and opens the inner door, and when reversed and moved throughout its range in the other direction it successively closes the inner door, locks it shut and opens the outer door.

10. The combination of a chute, a branch chute thereto, an inner and an outer pivoted door in the branch, a gear connected to turn when the outer door turns, a second gear connected to turn when the inner door turns and a third gear in position to operate either 70 of the other gears and positioning each in the closed position when moving the other.

11. The combination of a chute, a branch chute thereto, an inner and an outer pivoted door in the branch, a driven gear connected 75 to the inner door, a driven gear connected to the outer door, a driving gear positioning and mating with both the others, the perimetral portion of the driving gear having an arc contour circumferentially adjacent to each end of the toothed portion and a perimetral portion adjacent to the gear teeth on each of the other gears adapted to fit and lock against the arc contours.

12. The combination of a chute, a branch chute thereto, an inner and an outer pivoted door in the branch, driving mechanism having teeth and adjacent locking portions, and two driven gears connected respectively to turn when the two doors turn, each having 80 teeth and a portion adjacent to the teeth, engaging with and locked against the driving mechanism.

13. The combination of a chute, a branch chute therein, inner and outer pivoted doors in the branch adapted to open and shut, two gears one connected to each door, a third gear positioning the first two gears, engaging 85 one of them to open and close the outer door while locking the gear of the inner door, or engaging the other to open and close the inner door while locking the outer door, the gear teeth of the two gears interfitting but part of the way around and these gears having concavities, surfaces cooperating 90 with convex portions of the surface upon the third gear to form Geneva stop mechanism for each gear.

14. A pair of doors and driving gearing for the doors adapted to drive one door at a 95 time and lock the other door, comprising a pair of driven gears connected with the doors and having each a portion of the surface provided with teeth and an adjacent portion provided with a concaved contour 100 and with a driving gear located between the driven gears, having teeth about a portion only of its surface and the remainder of the surface convexed to fit with the concaved surfaces of the respective driven gears to 105 hold one driven gear against door opening

movement while the driving gear is driving the other driven gear.

15. A pair of cooperating doors and gearing for opening the doors, comprising a common driving gear and driven gears connected with the doors cooperating with the driving gear, the driven gears having opposite directions of closing movement, each intermeshing with the driving gear to be driven by it for a portion of a turn and free 75 from the driving engagement for the remaining part of the turn of the driving gear while the other gear is being driven.

16. A passage way, spaced pivoted doors 80 therein and a combined driving and stop mechanism for opening either door while holding the other closed and comprising a driving gear having two sets of teeth and adjacent each set for a portion of its circumference, a convex locking surface, and a pair of driven gears respectively connected operatively to the doors and each having teeth meshing respectively with the two sets upon the driving gear and a concaved locking surface adjacent the teeth adapted to engage 85 respectively with convex locking surfaces of the driving gear and arranged so that the tooth engagement between the driving gear and either driven gear will be coincident with locking surface engagement between 90 the driving gear and the other driven gear.

17. The combination of a chute, pivoted doors therefor having parallel shafts, a driving gear having an axis parallel to the shafts, having a neutral position and movable in both directions therefrom and driven gears on the door shafts operating the doors both locked against the driving gear in its neutral position, alternatively operated with opposite movements of the driving gear and each locked against the driving gear when the other is operated.

18. The combination of a chute, a branch chute thereto, inner and outer doors in the branch, common means for opening and closing the doors, operative with respect to either door when the other is closed, and means, effective by reason of the positions of the doors, for locking the common means 105 from moving either door unless the other 110 door is closed.

19. The combination of a chute, a branch chute leading thereto, inner and outer swinging doors for the branch, a driving gear for operating both doors, driven gears 120 operatively connected with the two doors one at a time and cooperating stop mechanism between the driven gears and the driving gear holding each driven gear against movement tending to open its door while 125 the other driven gear is being operated, the cooperating stop mechanism also holding both driven gears locked against door opening movement at one position of the driving mechanism.

20. A passage way, spaced pivoted doors therein and a combined driving and stop mechanism for opening either door while holding the other closed and comprising a
5 driving gear having two sets of teeth and adjacent each set for a portion of its circumference, a convex locking surface, and a pair of driven gears respectively connected operatively to the doors and each having
10 teeth meshing respectively with the two sets upon the driving gear and a concaved lock-

ing surface adjacent the teeth adapted to engage respectively with convexed locking surfaces of the driving gear and arranged so that the toothed engagement between the 15 driving gear and either driven gear will be coincident with locking surface engagement between the driving gear and the other driven gear, the driving gear in one position locking both driven gears.

GAIL D. BEAVER.
